US00D894257S

(12) **United States Design Patent** (10) **Patent No.:** **US D894,257 S**
(45) **Date of Patent:** **** Aug. 25, 2020**

(54) **GIMBAL**

(71) Applicant: **SZ DJI TECHNOLOGY CO., LTD.**,
Shenzhen (CN)

(72) Inventors: **Min Kim**, Shenzhen (CN); **Zhi-Hui Zhu**, Shenzhen (CN); **Xiao-Yu Tian**, Shenzhen (CN)

(73) Assignee: **SZ DJI TECHNOLOGY CO., LTD.**,
Shenzhen (CN)

(**) Term: **15 Years**

(21) Appl. No.: **29/704,737**

(22) Filed: **Sep. 6, 2019**

Related U.S. Application Data

(63) Continuation of application No. 29/688,578, filed on Apr. 23, 2019, now Pat. No. Des. 866,647, which is a continuation of application No. 29/632,363, filed on Jan. 8, 2018, now Pat. No. Des. 857,786.

(57) **CLAIM**

The ornamental design for a gimbal, as shown and described.

DESCRIPTION

FIG. 1 is a front perspective view of a gimbal showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict environmental structure and boundaries only and form no part of the claimed design to be patented.

1 Claim, 8 Drawing Sheets
